UNITED STATES PATENT OFFICE.

OTTO SCHAMBECK, OF NEW YORK, N. Y.

LACE-STRING.

SPECIFICATION forming part of Letters Patent No. 550,422, dated November 26, 1895.

Application filed July 2, 1895. Serial No. 554,745. (No model.)

To all whom it may concern:

Be it known that I, OTTO SCHAMBECK, a citizen of Germany, and a resident of New York city, New York, have invented an Improved 5 Lace-String, of which the following is a specification.

This invention relates to a lace-string which is so constructed that it need not be tied at the ends and that it will be held perfectly taut 10 after being once secured to the lace-hooks.

In the accompanying drawings, Figure 1 is a perspective view of a shoe provided with my improved lace-string. Fig. 2 is a perspective view of the string; Fig. 3, a detail 15 showing the end of the string engaged by one of the lace-hooks; Fig. 4, an enlarged cross-section on line 4 4, Fig. 2; and Fig. 5, an enlarged longitudinal section on line 5 5, Fig. 2.

My improved lace-string is composed of an 20 inelastic body *a* and of elastic ends *b*, secured to such body. The body *a* is formed of textile tubing and the elastic ends *b* are formed of solid rubber filaments, which are slipped a short distance into the tubing and are secured 25 thereto by suitable clasps *c*. Each clasp is preferably made in the form of a ring that embraces the tubing at its junction with the filament. An indentation *c'* of the clasp forces the tubing inward and into a fold of

the rubber and thus insures a very reliable 30 connection. At the outer ends the filaments *b* may be provided with the usual metal tips *d*.

In use the shoe *A* or other article of apparel is laced in the usual manner and then the elastic ends of the filaments *b* are slipped 35 under the lace-hooks *e*. These hooks will compress the filaments at their point of engagement, Fig. 3, and will in this way securely hold the lace-string in place without requiring any tying of the same. Moreover, 40 the elastic ends of the string will exert a constant strain on its inelastic body, so that the string will be always held perfectly taut from end to end.

What I claim is—

1. A lace string composed of a tubular textile body, elastic ends entering the same, and clasps for securing such ends to the body, substantially as specified.

2. A lace string composed of a tubular textile body, elastic filaments entering the same, indented annular clasps, and of tips secured to the ends of the filaments, substantially as specified.

OTTO SCHAMBECK.
